DESIGN FOR A WATER SHOE

Donna Louise Fenlason, New York, N. Y.

Application May 20, 1948, Serial No. 146,489

Term of patent 14 years

(Cl. D7—4)

To all whom it may concern:

Be it known that I, Donna Louise Fenlason, a citizen of the United States of America, residing in the Borough of Manhattan, city of New York, county of New York, and State of New York, have invented a new, original, and ornamental Design for a Water Shoe, of which the following is a specification, reference being had to the accompanying drawing, forming part thereof.

Figure 1 is a side elevational view of a water shoe, showing my new design.

Figure 2 is a rear elevational view of the water shoe shown in Figure 1.

Figure 3 is a front view in perspective, enlarged, of the water shoe shown in Figure 1, with the vamp strap in a tightened position.

I claim:

The ornamental design for a water shoe, as shown and described.

DONNA LOUISE FENLASON.
